UNITED STATES PATENT OFFICE.

WILLIAM F. DURNAN, OF ROCHESTER, NEW YORK, ASSIGNOR TO BASTIAN BROTHERS COMPANY, OF ROCHESTER, NEW YORK, A CORPORATION OF NEW YORK.

MEDALLION.

1,055,453.

Specification of Letters Patent. Patented Mar. 11, 1913.

Application filed September 8, 1910. Serial No. 581,074.

To all whom it may concern:

Be it known that I, WILLIAM F. DURNAN, a citizen of the United States, and resident of Rochester, in the county of Monroe and

5 State of New York, have invented certain new and useful Improvements in Medallions, of which the following is a specification.

This invention relates to medallions, and 10 has for its object a simple, cheap construction whereby a decorated panel with a superimposed transparent plate are framed and locked within it.

In the drawings:—Figure 1 is a front 15 view of a medallion embodying the invention; and Fig. 2 is a central, cross-section.

1 shows a frame made of metal and recessed centrally to receive both the decorated panel 2 and a thin transparent celluloid plate 3. A flange 4 is formed around 20 the decorated panel, and, by means of bur-

nishing, the metal of this flange is caused to flow inwardly till it overhangs the celluloid plate 3 in the form of a ledge 5, thus securing it in place.

25

I claim:—

A medallion comprising a substantially flat base, a flange formed integral with and projecting from the face of the base at a substantial distance within the edge thereof, so as to leave a wide, flat marginal portion surrounding the flange, a decorative panel lying within said flange and against the base, and a transparent plate covering said panel, the edge of the flange being bur- 30 nished inwardly over the transparent plate to retain the plate and the panel in place within the flange.

35 WILLIAM F. DURNAN.
